UNITED STATES PATENT OFFICE.

FREDERICK C. OVERBURY, OF HILLSDALE, NEW JERSEY, ASSIGNOR TO THE FLINTKOTE COMPANY, OF BOSTON, MASSACHUSETTS, A CORPORATION OF MASSACHUSETTS.

STRIP ROOFING UNIT AND PROCESS OF MANUFACTURE.

Application filed November 9, 1922. Serial No. 599,871.

This invention relates to roofing and the process of manufacture whereby a roofing constructed of fibrous material such as felt impregnated with water resistant material

5 may be made to present a substantial appearance on the roof without requiring that the material from which it is made shall be of more than ordinary thickness, the material preferably being made up in strip form and 10 each strip simulating a plurality of individual roofing units.

For this purpose the material is folded in such a manner that the portion exposed to the weather is at least twice its normal thickness, the two or more layers being so united as to form a substantially integral structure. The strip may be surfaced as by the application of granular material thereto to improve its weather-resisting qualities.

15 For a more complete understanding of this invention reference may be had to the accompanying drawings in which

Figure 1 represents in perspective a piece of roofing material in strip form.

20 Figure 2 shows a piece of the strip folded preparatory to forming into the finished strip units.

Figure 3 is a view similar to Figure 2, but showing edge notches in the strip to form tabs 30 simulating shingles.

Figures 4 and 5 are perspectives before and after folding, respectively, showing another method of cutting the tabs.

Figures 6, 8, and 10 are fragmentary plans 35 showing other forms in which the sheet may be cut.

Figures 7, 9, and 11 are perspectives showing the sheets cut as in Figures 6, 8, and 10, respectively, and partially folded to their 40 finished forms.

Figures 12 and 13 show still another manner of cutting and folding the material.

A strip of felt as shown in Figure 1 at 1, preferably saturated and either before or 45 after being coated with asphalt in the usual manner, is passed through a suitable folding machine so that its side edges 2 are folded at 7 in the manner shown in Figure 2 against one face of the sheet. The opposite folded

50 edges may then be notched as shown at 3 in Figure 3 to simulate shingles and the strip may then be cut longitudinally through its central portion along the line 4 to form two double strips, each strip having an upper layer 5 and a lower layer 6, the lower layer ex-

tending from the folded edge 7 at least to the upper edges of the notches 3. As shown in these figures the lower layer extends co-terminous with the upper layer.

If the sheet material has been saturated 60 only before the folding is effected, it is then coated with the coating asphalt in the usual manner so that the two layers of the double thick unit become united together in a substantially integral structure. In case the coating has been applied before the sheet is folded, it is preferable to pass the unit between heated rollers in order that the coatings may unite where the upper and lower layers are in contact so that they may be firmly united. 65

In Figure 3 the notches 3 are shown as cut entirely through both layers of material. If desired, however, they may be made to pass through only the upper layer as shown for example in Figures 4 and 5, in which case the notches 30 may be cut in the material before it is folded and extend in one direction to the line of fold at 10 so that when the material is folded as shown in Figure 5 the notches 30 are entirely underlaid with the lower layer 80 of the material and they extend to the folded edge 10 which is exposed to the weather.

Various other ways of cutting the material may be employed in order to produce varying designs of the finished material, for example, in Figures 6 and 7 slots 31 extending across the fold line 12 are shown. The material is then folded as indicated in Figure 7 crosswise of the slots forming rectangular tabs similar to those shown in Figure 3. 85

In Figures 8 and 9 somewhat diamond shaped openings 32 symmetrically disposed on either side of the fold line at 13 are shown, the material when folded presenting hexagonal ended tabs 33 as shown in Figure 9. 90

In Figures 10 and 11 substantially hexagonal cut-outs 35 are employed adjacent one edge of the material. It is then folded about the line 14 symmetrically related to the opening 35 to form when folded the hexagonal tabs 100 36 of Figure 11, the lower layer 37 in this construction extending only to the upper edge of the cut-out portions.

In Figures 12 and 13 a further modification is shown in which the material is folded twice, 105 for example, first along the line 15 to form a layer 16 and then again in the same direction along the line 17 to form a layer 18, both underlying the main portion of the sheet as shown in Figure 13, the portion 16 lying be- 110

tween the body of the sheet and the portion 18. In this case, as shown, slots 20 are cut through the upper layer of the material and underlaid by the layers 16 and 18. In this 5 form the portion exposed to the weather is of triple thickness while extending therefrom is a single thickness for underlying the adjacent course. While as shown rectangular notches are employed passing through the outer layer 10 or thickness of the material, it is evident that they could if desired be cut through one or more thicknesses and they could be of various shapes as desired. This last construction affords a very substantial thickness of 15 material exposed to the weather and is susceptible of various forms of treatment. For example, the granular coating which is often placed on the exposed surfaces of this type of roofing may be embedded in the upper surface 20 of the main portion of the sheet while being omitted from the portion 18 which rests against the roof where it is not exposed to the weather. The portion 16 may also be coated with granular material if desired, this 25 being particularly desirable where the notches 20 extend only through the body portion of the sheet, the granular material being then exposed beneath the notches 20. It is also to be noted that the underlying layers of the 30 material extend at least to the upper edges of the cut-outs and that the whole unit is so formed that the layers are united, as for example by the asphaltic material with which they are impregnated or coated, or both, to 35 form a substantially unitary construction without visible seams. The provision of the folded edge of the layers to be exposed to the weather prevents any possibility of moisture finding its way to any improperly impregnated felt within the body of the material 40 and the various layers so united form a construction which will not curl or warp in use.

The strips illustrated in the drawing are shown as of a length equal to that of the cus-

tomary strip shingle, but it is obvious that 45 these may be cut by transverse cuts into shorter finished elements; or a longer strip than shown may be slotted, folded and slit, then cut transversely into finished elements of desired length. 50

While two and three folded layers have been shown, it is of course evident that more layers might be employed if desired without departing from the spirit or scope of this invention and that various other changes and modifications might be made without departing from the scope of the invention as defined by the appended claims. 55

I claim:

1. The method of making roofing which 60 comprises folding opposite edges of a piece of sheet material over against one face thereof, then cutting said folded sheet into roofing units.

2. The method of making roofing which 65 comprises folding opposite edges of a piece of sheet material over against one face thereof, then cutting said folded sheet in two between said edges and each portion into roofing units. 70

3. The method of making roofing which 75 comprises folding opposite edges of a piece of sheet material over against one face thereof, then cutting said folded sheet into roofing units, the edges formed by the folding operation forming the edges exposed to the weather when the units are laid.

4. The method of making roofing which 80 comprises folding opposite side edges of a strip of sheet material against the face thereof, notching out the folded edges to form individual roofing unit simulating tabs, and cutting said sheet longitudinally intermediate 85 said folded edges and transversely into desired lengths.

In testimony whereof I have affixed my signature.

FREDERICK C. OVERBURY.
